UNITED STATES PATENT OFFICE.

CLIFFORD W. VESSY, OF CLEVELAND, OHIO, ASSIGNOR TO ANCHOR CAP & CLOSURE CORPORATION, OF LONG ISLAND CITY, NEW YORK, A CORPORATION OF NEW YORK.

PACKAGE AND CLOSURE MEANS.

Application filed February 27, 1924. Serial No. 695,393.

This invention relates to a package and closure means for the same as well as a novel form of container.

The general art of seals for containers, for the purpose of understanding this invention, may be classified into two types, namely, friction seals and hermetic seals. Friction seals to be considered are those in which a cap is held in position by the friction of some portion of the cap on the side wall or under a ledge on the container. Hermetic seals referred to are those in which the cap is held in position by means of a gasket which is forcibly seated against the side wall of the container. In both of these types of seals it will be appreciated that the cap must fit tightly on the container, and where the container is made of glass it is sometimes difficult to remove the closure cap without danger of breaking of the container.

The present invention overcomes the difficulties of the known art by providing a construction in which provision is made for wedging or forcing the cap from the container by forces which may be applied to the skirt of the cap in the direction of its length. This is brought about by providing on the container a suitable abutment associated with the side wall of a container a sufficient distance from the mouth thereof so that a space will always be left between the abutment and the edge of the cap when the cap is seated in position on the container to form a sealed package. This abutment and the space adjacent thereto permits the user to insert a suitable implement or coin between the abutment and the edge of the cap so that force may be applied directly to the edge of the cap by using the abutment as a fulcrum, thereby applying a direct line stress to the cap most effectively to overcome the sealing forces by sliding the cap from the end of the container.

The principal object of the present invention is a package comprising a side seal cap mounted thereon with an abutment spaced apart from the edge of the cap and being adapted to comprise a fulcrum to pry the cap from the container.

Another object of the present invention is a container comprising a sealing zone adjacent the mouth thereof, an abutment spaced apart from said zone, and an undercut portion between the sealing zone and the abutment whereby suitable depth may be ob-

tained to insert an instrument for removing the side seal cap from said container.

Another object of the present invention is a sealed package comprising a container with a closure cap seated thereon to form a suitable seal, with the edge of said cap extending outwardly from said container and a projection extending from said container substantially equal to, or slightly greater than the maximum diameter of a closure cap and adjacent the lower edge thereof whereby the projection on the container protects the said closure cap and prevents loosening the seal during shipping or handling.

A still further object of the present invention is a sealed package comprising a container provided with an annular bead adjacent the mouth thereof, a restricted portion above the bead, a sealing zone between the restricted portion and the end of the container, with a closure cap having a skirt provided with an inwardly curved bead, with the curve thereof of such length that the end of the sealing zone terminates above the minimum diameter of the skirt of the cap whereby there is a tendency of the bead of the cap to interlock under the edge of the sealing zone.

Other and further objects of this invention will in part be obvious and will in part be pointed out hereinafter by reference to the accompanying drawings, wherein like characters are used to represent like parts throughout the several figures thereof.

It is recognized that the present invention may be carried out in constructions other than those herein specifically disclosed so therefore it is desired that the disclosure in this application shall be considered as illustrative and not in the limiting sense.

Figure 1 is an elevational view of a package embodying one form of the present invention.

Figure 2 is an enlarged view showing a portion of the upper part of a package in section.

Figure 3 is a detail view of a slight modification of the invention shown in Figure 2.

Figure 4 is a detail view illustrating one form of the invention with the cap removed.

Figure 5 illustrates the use of a suitable instrument such as a coin for prying off the cap.

Referring now to the drawings which il-

- lustrate the preferred form of the invention, the disclosure cap A is provided with a cover portion 1 from which depends a skirt 2, which skirt preferably is provided with concave bead 4 that is corrugated in the concave part thereof to form friction sealing members and is provided on its lower edge with a suitably formed wire edge 5 as is common in the art. As a matter of fact, this closure cap is merely used for illustrative purposes of a general type of cap which may be used in carrying out this invention, and the specific cap shown is that disclosed in the patent to Ramsey 15 Patent 1,327,963, January 13, 1920. This cap, or a cap of this type either a friction seal or a hermetic seal, is adapted to set upon the container B, which is a packers jar provided on its upper portion with a sealing zone 6 against which the inner portions of the concave corrugations are adapted to set. The sealing zone 6 is of slightly larger diameter than the minimum diameter between the inner portions of diametrically opposed corrugations on the cap illustrated so that when the cap is forced over the sealing zone the skirt of the cap is slightly stretched and thereby forms a very secure friction seal between the cap and the container, which seal is too tight to be broken by ordinary manual manipulation. The wire edge 5 of the cap stands a considerable distance away from the side wall of the container, and this distance is accentuated by the undercut groove 35 7 which is just below the sealing zone 6. An annular shelf 8 which extends outwardly and is formed into an annular bead 9 is spaced a sufficient distance from the end of the container to always provide a space 40 10 between the wire edge 5 of the cap and the shelf 8. This space facilitates the insertion of some implement such as a coin 11 into the space, which coin may be twisted between the shelf 8 and the edge 5 to force 45 the cap from sealing zone 6, thereby opening the package.

Figure 3 illustrates a slight modification of the present invention in which the sealing zone 12 is of a length which is shorter than 50 the distance from the top of the cap to the crown of the arch formed by the corrugations in the concave bead.

This causes the resilient portion of the

bead to interlock under and beneath the sealing zone and thereby provides a very 55 tight secure friction seal.

It will be observed that the bead 9 extends outwardly substantially equal to or slightly beyond the wire edge, so that if several packages of this type are set side by side, 60 the beads 9 will contact and prevent the wire edges of the caps from striking each other, which, if permitted, would tend to destroy the seal and would permit the caps to be loosened so as to be easily removed 65 and possibly come off during handling or transit. The bead 9, therefore, not only reinforces the shelf 8, but comprises a guarding ring or protection for the sealing cap.

Having thus described my invention, what 70 I claim is:

1. A package comprising a container having an annular horizontally projecting abutment spaced from the mouth thereof, a substantially cylindrical sealing zone adjacent 75 the mouth of the container, and an annular recess between the abutment and the sealing zone; in combination with a cap comprising a skirt having an annular inwardly formed concave bead frictionally engaging the cylindrical zone of the container, said annular bead in the skirt being corrugated transversely to provide for expansion, and a wire edge on said skirt spaced from the annular abutment and from the bottom of the annular recess, whereby the package may be opened either by pressing the sealing zone of the container against the cap bead to flatten and expand the same or by placing an instrument under the wire edge and using 85 the annular abutment as a fulcrum.

2. A package comprising a container having an annular projecting abutment spaced from the mouth thereof, a substantially cylindrical sealing zone adjacent the mouth of 90 the container, an annular recess between the abutment and the sealing zone, in combination with a cap having an annular inwardly formed corrugated bead in the skirt thereof adapted to engage said cylindrical sealing zone, and an outwardly flared wire edge on the said skirt spaced from the annular abutment and from the bottom of the annular recess.

CLIFFORD W. VESSY.
